UNITED STATES PATENT OFFICE

158,543

PORTABLE DEHUMIDIFYING APPARATUS

Verne W. Aubel, Jr., Millburn, N. J., assignor to
Allied Chemical & Dye Corporation, New York,
N. Y., a corporation of New York

Application May 4, 1949, Serial No. 2,440

Term of patent 14 years

(Cl. D16—2)

To all whom it may concern:

Be it known that I, Verne W. Aubel, Jr., a citizen of the United States of America, residing at Millburn, in the county of Essex and State of New Jersey, have invented a new, original, and ornamental Design for a Portable Dehumidifying Apparatus, of which the following is a specification, reference being had to the accompanying drawings, forming part thereof.

In the drawings:

Figure 1 is a perspective view showing the front and one side of a portable dehumidifying apparatus embodying my new design;

Figure 2 is a front view thereof;

Figure 3 is a top plan view;

Figure 4 is a side view; and

Figure 5 is a rear view thereof.

Figures 2, 3, 4 and 5 are shown on a reduced scale.

I claim:

The ornamental design for a portable dehumidifying apparatus, substantially as shown.

VERNE W. AUBEL, JR.
